UNITED STATES PATENT OFFICE.

CHARLES E. HOPKINS, OF WASHINGTON, DISTRICT OF COLUMBIA.

CIGARETTE-MAKER.

1,315,838.

Specification of Letters Patent.

Patented Sept. 9, 1919.

Application filed January 27, 1919. Serial No. 273,383.

To all whom it may concern:

Be it known that I, CHARLES E. HOPKINS, a citizen of the United States, residing at Washington, in the District of Columbia, have invented new and useful Improvements 5 in Cigarette-Makers, of which the following is a specification.

This invention has reference to a cigarette making device, and has for its primary object to produce a simple, cheap and thoroughly effective means whereby tobacco may be effectively packed in a paper cartridge or casing to produce a cigarette.

A further object of the invention is to 15 produce a cigarette making device in which the parts constituting the same may be caged one within the other and inclosed by a suitable detachable cap, when the device is not in use, so that the same may be conveniently 20 carried in the pocket of the user.

It is a further object of the invention to produce a construction and arrangement of parts wherein one end of a cigarette formed by the device will be partly projected 25 through the outer member or barrel of the construction so that the same may be readily lifted out of said barrel for use.

It is a further object of the invention to produce a cigarette forming device including 30 a barrel having one of its ends closed and its said closed end provided with an opening; to arrange a packing tube or mold in the barrel after a cigarette paper has been wound around the said tube, the edges 35 thereof pasted together and the lower end crimped or bent inwardly over the inner edge of the packing tube, the said packing tube having its outer end formed with a flared receiving member; to arrange in the 40 packing tube a packing member in the nature of a plunger which extends through the opening in the barrel, and to provide means for locking the tube in the barrel so that the said tube will be held against movement 45 when the packing member is reciprocated to draw and pack tobacco in the tube, and so that the paper cartridge can not become disassociated from the tube nor the end thereof from between the inner end of 50 the tube and the closed end of the barrel so that a perfect cigarette may be formed by the device. The head of the packing tube is designed to be positioned in a tobacco receptacle and when reciprocated draws the

tobacco therefrom into the packing tube, 55 packing the said tobacco therein, the packing member is locked to the barrel when sufficient quantity of tobacco has been received in and packed in the tube, after which the casing is unlocked and removed from 60 the barrel, leaving the cigarette held in said barrel by the locked packing member, one end of the cigarette projecting a suitable distance outward of the barrel. The packing member is then released from the barrel 65 and drawn centrally through the cigarette, permitting the removal of the cigarette from the barrel.

Other objects and advantages will present themselves as the nature of the invention is better understood, reference being had to the accompanying drawings, in which:

Figure 1 is a perspective view of the complete device.

Fig. 1^a is a similar view of the tubular cap.

Fig. 2 is a perspective view of the device in operative position.

Fig. 3 is a greatly enlarged vertical longitudinal sectional view through the device as illustrated in Fig. 2, the dotted lines showing the arrangement of the tubular cap when positioned upon the barrel.

Fig. 3^a is a sectional view approximately 85 on the line 3—3 of Fig. 3.

Fig. 4 is an elevation of the packing member or plunger.

Fig. 4^a is a bottom plan view thereof.

Fig. 5 is a perspective view looking toward the closed end of the barrel and showing the packing member locked thereto.

Fig. 6 is a detail elevation showing the rod of the packing member or plunger projecting through the closed end of the barrel 95 as disclosed in Figs. 2 and 3.

Fig. 6^a is a bottom plan view of the construction as illustrated in Fig. 6.

Fig. 7 is a view similar to Fig. 6 but showing the packing or plunger rod locked to the barrel.

Fig. 7^a is a plan view of the device illustrated in Fig. 7.

Fig. 8 is a side elevation of the packing tube or mold.

Fig. 8^a is a sectional view approximately 105 on the line 8—8 of Fig. 8.

Fig. 9 is an elevation of the barrel.

Fig. 9^a is a sectional view approximately on the line 9—9 of Fig. 9 and looking in the direction of the arrows.

Fig. 10 is an elevation of the locking sleeve for the barrel and packing tube.

As disclosed in Fig. 1 of the drawings, all of the elements constituting the improvement are designed to be arranged in the outer member or barrel of the device and to be retained therein by a removable tube or cap member. The cap member, as indicated by the dotted lines in Fig. 3 of the drawings frictionally contacts with the outer and flared mouth of the packing tube or mold and with the locking sleeve on the barrel, so that while the cap tube may be readily removed the device, as a whole, in its inoperative position may be conveniently carried in the vest pocket of the user. Also it should be stated that when the device is not in use the packing or plunger member is withdrawn from the guide opening in the closed end of the barrel, and reversed and again inserted in the barrel so that the head portion thereof will rest upon the bottom of the barrel.

The elements constituting the improvement may be made of any desired material and are of a size whereby a cigarette of conventional form may be made.

Machine-made cigarettes are objectionable to the majority of smokers because the tobacco used in the manufacture thereof does not appeal to individual tastes, some preferring stronger and others lighter tobacco than is used in such cigarettes. In addition to this, the cigarette is either too tightly or too loosely packed, the former fault being most general, and in which event the smoker rolls the cartridge in order to loosen the tobacco therein which most generally results in producing a too-loosely packed cigarette, and, of course, a loss of considerable tobacco. The majority of cigarette smokers would prefer to make their own cigarettes, as they could then use a tobacco best suited to their taste, but the ordinary hand rolling of cigarettes requires a great amount of practice before the same is made perfect and the majority of smokers do not care to take the time to perfect themselves in that art. With my improvement, it will be noted as the description progresses, a cigarette may be formed in an easy, quick and satisfactory manner.

Referring now to the drawings in detail, the numeral 10 designates the outer member of the improvement which is in the nature of a cross sectionally round tube or barrel. The barrel is of an equal cross sectional diameter throughout and has one of its ends closed as at 11. The closed end is approximately centrally formed with a rectangular opening 12, and to the opposite sides of this opening, at diagonally opposite

points are slight protuberances in the nature of lugs 13.

Slidable on the barrel 10, at the open end thereof is a sleeve 14. This sleeve is limited in its inward movement by contacting engagement with stop lugs 15 which are formed on a barrel 10, and when the sleeve is in such position the outer edge thereof is approximately flush with the open end of the barrel. The sleeve, from its outer end, 70 is provided with an elongated longitudinally extending slot 16 having angle branch passages 17 and 18 respectively, adjacent the ends of the slot 16. On the barrel 10 is a pin 19. This pin is designed to be received 80 in the slot 16 when the sleeve 14 is moved longitudinally of the barrel in either direction. When the sleeve is moved outward of the barrel and partly turned on the barrel the pin is received in the passage 17 of the 85 slot 16. When the sleeve is moved inward on the barrel and partly turned the pin is received in the passage 18 of the slot 16.

The packing tube is indicated by the numeral 20 and is of a greater length than the 90 barrel 10. The outer end of the packing tube is flared as at 21, and this flared portion provides the mouth of the tube. The flared mouth has an outwardly extending pin 22 designed to receive the slot 16 of the 95 sleeve 14 and the outer passage 19 of the said slot, when the sleeve is turned on both the barrel and tube to lock the tube in the barrel. This is an important feature of the invention as will be presently apparent.

The tobacco packing member comprises a cross sectionally rectangular rod 23 which is of a greater length than the tube and barrel. The rod is of a size to snugly pass through the opening 12 in the barrel, and the said 105 rod has its outer end provided with a head 24. The rod, at a suitable distance from its outer end has its edges provided with oppositely disposed notches 25, the purpose of which will presently be set forth.

In operation a cigarette paper 26 is arranged around the packing tube 20, the lapping edges of the paper being sealed in the usual manner to produce a cartridge. The lower end of the cartridge is bent inwardly 115 over the lower edge of the packing tube as indicated by the numeral 27 and as disclosed in Fig. 3 of the drawings. The packing tube and cartridge are now positioned in the barrel. The locking sleeve 14 is moved outwardly of the barrel so that the passages 17 and 18 in the slot 16 thereof are brought opposite the pins on the barrel and tube. The sleeve is partly turned to bring these pins in the said passages, thus locking the 125 tube in the barrel and tightly compressing the bent or inturned end of the cartridge between the inner end of the tube and the closed end of the barrel. The packing or plunger rod 23 is passed through the pack- 130

- ing tube and the closed end of the barrel. The mouth of the packing tube is inserted in a receptacle containing tobacco from which the cigarette is to be formed, the head 24 of the packing member 23 being also arranged in the said receptacle and the packing member is given a reciprocatory movement until sufficient tobacco has been drawn from the receptacle into the packing tube.
- 5 10 The reciprocation of the member 23 through the tube and barrel permits of the notches 25 in the rod thereof acting upon the tobacco to compress the same toward the bottom of the cartridge, and when the head 24 is brought 15 against the tobacco and compresses the same sufficiently the notches 25 will be arranged opposite the walls of the opening 12 in the closed end of the barrel. The rod is now given a half turn so that the sides thereof 20 will contact with the lugs 13. The locking sleeve 14 is moved to unlocking position on the barrel 10 with respect to the tube 20. The tube 20 is turned in the same direction as was the rod 23 to loosen the same and to 25 permit the withdrawal of the said tube from the cartridge 26. The packing member or plunger is then turned so that the rod 23 may be withdrawn through the opening in the closed end of the barrel, and through 30 the tobacco in the cartridge. The rod is comparatively thin and the packed tobacco in the cartridge readily fills the space previously occupied by the said rod. In this manner a perfectly formed cigarette is easily 35 and quickly produced. The end of the cigarette projects a suitable distance through the open end or mouth of the barrel and this end may be readily grasped to remove the cigarette from the barrel.
- 40 45 When the device is not required for use the tube is arranged in the barrel and the packing member or plunger is arranged in the tube. The plunger member is turned end for end, that is, the head thereof rests on the closed end of the barrel. A tubular cap 28 is inserted over the open end of the barrel and is brought to frictional engagement with the locking sleeve, as indicated by the dotted lines in Fig. 3 of the drawings.
- 50 55 It is believed, from the foregoing description, when taken in connection with the drawings, that the simplicity of the construction and the advantages thereof will be apparent without further detailed description.
- Having thus described the invention, what is claimed as new, is:—
1. In a cigarette forming device, a barrel having a closed end provided with an opening, a packing tube in the barrel designed to have arranged therearound a paper cartridge one end of which being bent inward over the end of the packing tube, means for locking the packing tube to the barrel, a rod 60 arranged centrally through the packing tube and passing through the closed end of the barrel, said rod having its outer end headed, and means for locking the rod to the barrel when the head thereof has been brought into the packing tube a predetermined distance. 70
2. In a cigarette forming device, a barrel having one of its ends closed and its said closed end provided with an opening, a slideable sleeve on the open end of the barrel, means for limiting the movement of the sleeve in both directions, a packing tube in the barrel designed to have a paper cartridge arranged thereon and said cartridge designed to have one of its ends bent over one end of said tube, and said tube designed to be engaged by the locking sleeve for holding the same in the barrel, a rod of a greater length than the barrel and tube passing through the opening in the closed end of the barrel, said rod having its outer end headed, and means for locking the rod to the barrel when the head thereof has been brought into the packing tube a predetermined distance. 75
3. A cigarette forming device including a barrel having a closed end provided with an opening, a sleeve slideable over the open end of the barrel, said sleeve having a slot from the outer end thereof provided with two lateral passages, a pin on the barrel designed to be received in one of the passages when the sleeve is moved outward of the barrel and in the other passage when the sleeve is moved inward on the barrel, stop lugs for limiting the inward movement of the sleeve, a packing tube designed to be received in the barrel and to have arranged therearound a paper cartridge one end of which being bent over the inner end of the said tube, the tube being of a greater length than the barrel and having a pin at its outer end to receive the outer passage of the slot in the sleeve, a rod passing through the opening in the closed end of the barrel, said rod being of a greater length than the tube or barrel and having its outer end headed, and means for locking the rod to the barrel when the head thereof has been brought into the tube a predetermined distance. 80
4. A cigarette forming device including a barrel having one of its ends closed and its said closed end provided with an opening, a packing tube in the barrel designed to have arranged therearound a paper cartridge one end of which being bent over the inner end of the packing tube, a rod arranged centrally through the packing tube and passing through the opening in the barrel and designed to be reciprocated in the barrel, said rod having its outer end headed, and means for locking the rod to the barrel when the head thereof has been brought into the packing tube a predetermined distance. 85
5. A cigarette forming device comprising a barrel, said barrel having a closed end provided with an opening, diagonally dis- 90

posed lugs on the outer face of said closed end arranged at the opposite sides of the opening, a packing tube in the barrel having one end projecting through the mouth of the barrel and its other end resting on the bottom of the barrel, said tube designed to have arranged therearound a paper cartridge, the lower edge of which being in turned over the lower edge of the tube, a packing member comprising a headed rod, said rod designed to be received in the opening in the closed end of the barrel, said rod having its edges provided with oppositely disposed notches whereby the rod may be turned when the notches are brought opposite the side walls of the opening to permit of the said rod contacting with the mentioned lugs, as and for the purpose set forth.

6. A cigarette making machine including a barrel, said barrel having a closed end provided with an opening, outwardly extending diagonally arranged lugs on the

outer face of the closed end disposed at the opposite sides of the opening in said end, a tobacco receiving tube of a greater length than the barrel arranged in the barrel and having its outer end flared outwardly, said tube adapted to have arranged therearound a paper cartridge the inner end of which being bent over the lower edge of the tube to contact with the closed end of the barrel, a reciprocatory rod passing through the opening in the closed end of the barrel and having its outer end headed, the edges of the rod being notched whereby the said rod may be given a half turn when the notches are brought in alinement with the walls of the opening in the closed end of the barrel to contact with the lugs and lock the rod on the barrel and a cap tube for the barrel for retaining the packing tube and rod in the barrel.

In testimony whereof I affix my signature.

CHARLES E. HOPKINS.
